ABSTRACT OF THE DISCLOSURE

A travelling-wave tube amplifier incorporating a periodic magnetic field focussing assembly which includes at least one magnetic member positioned closest to the collector of the amplifier which is capable of generating an asymmetrical magnetic field pattern for substantially preventing secondary emission electrons from leaving the collector structure.

The instant invention relates to travelling-wave tube amplifiers incorporating periodic magnetic field focussing means for focussing the electron beam of the travelling-wave tube, and more particularly to a travelling-wave tube amplifier of the type described wherein further means are provided to prevent deterioration of operating characteristics and eventual destruction of the tube amplifier by exerting suppressive control of the secondary electron emission from the collector of the tube amplifier.

In travelling-wave tube amplifiers of the type described, the direct current power consumed by the travelling-wave tube may be reduced in order to raise the operating efficiency of the device. To do this, it becomes necessary in operation to reduce the collector voltage level so that it is lower than the voltage of the slow-wave structure provided in the tube amplifier. With the collector voltage being lower than the voltage of the slow-wave structure, the secondary electron emission phenomenon causes secondary electrons emitted from the collector to be accelerated towards the slow-wave structure, thereby substantially increasing the slow-wave structure current. This leads to substantial over-heating of the slow-wave structure, and consequently to the deterioration of the vacuum condition within the tube envelope. This deterioration, in turn, causes various problems such as an increase of the ion noise in the structure and a significant reduction in useful operating life. Furthermore, the above-mentioned secondary electrons cause a significant reduction in the attenuation of the attenuator whose function is that of preventing oscillation so as to substantially raise the likelihood of the amplifier tube to oscillate and further increase electron beam noise.

In order to prevent the secondary electrons emitted from the collector to flow in the rearward direction, a conventional practice has been to deflect and trap the electrons by means of shaping the magnetic shield of the annular pole piece of the periodic magnetic field device positioned closest to the collector into an asymmetric configuration. It has been found, however, that deflection and capture of the secondary electron through the use of this method is unsatisfactory since only weak leakage flux is available near the collector of the amplifier tube. As a comparative example, a slow-wave structure of the conventional type travelling-wave tube amplifier, which does not employ any preventive measures to eliminate back-flowing secondary electrons and which employs a periodic

magnetic field structure, has a slow-wave structure current of 0.40 milliampere. The shaping of the annular pole piece of the periodic magnetic field device, which pole piece occupies the position closest to the collector, into an asymmetrical form having a sector-shaped cut with a central angle of 120° is found to reduce the slow-wave structure current to a value of 0.37 milliampere, which is an almost insignificant reduction. It has further been found that, if the annular pole piece disposed closest to the collector is provided with a semi-cylindrical member disposed within the central opening of the annular pole piece in place of a partially cut-away annular pole piece, this causes a reduction in the slow-wave structure current which, while less than 0.4 milliampere, is found to be greater than the resulting slow-wave structure current of 0.37 milliampere achieved through the use of a partially cut-away annular pole piece.

The instant invention is characterized by providing a travelling-wave tube amplifier wherein use is made of a periodic magnetic field focussing device which is so designed as to easily and effectively prevent the deterioration of the amplifier tube characteristics caused by the secondary electron emission from the collector.

In accordance with the instant invention, there is provided a travelling-wave tube amplifier comprising a magnetic structure disposed adjacent the collector end of the periodic magnetic field device which yields a magnetomotive force asymmetrical to the central axis of the magnetic field in order to deflect the electrons and hence significantly reduce backward current flow. The magnetic structure more specifically may be a permanent magnet having a substantially asymmetrical shape, or conversely, have a symmetrical shape and being provided with an asymmetrical by-pass element, or alternatively, being asymmetrically magnetized. Many of the above preferred embodiments produce an asymmetrical magnetic field component significantly greater than that which is capable of being produced through the use of conventional asymmetrical magnetic shields or asymmetric pole pieces, and further which is quite advantageous in its ability to deflect and trap secondary electrons emitted from the collector so as to prevent secondary electrons from flowing backwards to the slow-wave structure.

It is, therefore, one object of the instant invention to provide a novel travelling-wave tube amplifier structure having a periodic magnetic field focussing assembly which incorporates therewith means for significantly reducing direct-current power consumed by the travelling-wave tube.

Another object of the instant invention is to provide a novel periodic magnetic field focussing device for use in travelling-wave tube amplifiers, and the like, which includes means incorporated within the focussing device and disposed adjacent the amplifier tube collector structure for the purpose of significantly reducing the magnitude of current in the slow-wave structure.

Still another object of the instant invention is to provide a novel periodic magnetic field focussing device for use in travelling-wave tube amplifiers, and the like, which includes means incorporated within the focussing device and disposed adjacent the amplifier tube collector structure for the purpose of significantly reducing the magnitude of current in the slow-wave structure, said means being a magnetic device capable of generating a magnetic field asymmetrical to the field central axis so as to effectively deflect and trap secondary electrons emitted from the collector.

Yet another object of the instant invention is to provide a novel periodic magnetic field focussing device for use in travelling-wave tube amplifiers, and the like, which includes means incorporated within the focussing device

and disposed adjacent the amplifier tube collector structure for the purpose of significantly reducing the magnitude of current in the slow-wave structure, said means being a magnetic device capable of generating a magnetic field asymmetrical to the field central axis so as to effectively deflect and trap secondary electrons emitted from the collector, said means being a magnetic member having an asymmetrical configuration.

Still another object of the instant invention is to provide a novel periodic magnetic field focussing device for use in travelling-wave tube amplifiers, and the like, which includes means incorporated within the focussing device and disposed adjacent the amplifier tube collector structure for the purpose of significantly reducing the magnitude of current in the slow-wave structure, said means being a magnetic device capable of generating a magnetic field asymmetrical to the field central axis so as to effectively deflect and trap secondary electrons emitted from the collector, said means being a magnetic member which is asymmetrically magnetized.

A still further object of the instant invention is to provide a novel periodic magnetic field focussing device for use in travelling-wave tube amplifiers, and the like, which includes means incorporated within the focussing device and disposed adjacent the amplifier tube collector structure for the purpose of significantly reducing the magnitude of current in the slow-wave structure, said means being a magnetic device capable of generating a magnetic field asymmetrical to the field central axis so as to effectively deflect and trap secondary electrons emitted from the collector, said means being a magnetic member having a magnetic by-pass element shrouding a portion of said magnetic member so as to result in the production of an asymmetrical magnetic field.

These and other objects of the instant invention will become apparent upon consideration of the accompanying description and drawings in which:

FIGURE 1 is an axial sectional view showing the output side of a travelling-wave tube amplifier designed in accordance with the principles of the instant invention.

FIGURE 2 is a cross-sectional view taken along the line 2-2' of FIGURE 1.

FIGURES 2a and 2b are front views showing further alternative embodiments for the magnetic deflection structure of FIGURE 2.

FIGURE 3 is an axial sectional view showing an alternative embodiment of the instant invention.

FIGURE 4 is a cross-sectional view taken along the line 4-4' of FIGURE 3.

FIGURE 5 is an axial sectional view of the output side of still another embodiment of the instant invention.

FIGURE 6 is a sectional view taken along the line 6-6' of FIGURE 5.

FIGURE 7 is an axial sectional view of the output side of still another preferred embodiment of the instant invention.

FIGURE 8 is a cross-sectional view taken along the line 8-8' of FIGURE 7.

FIGURES 8a and 8b are front views showing further alternative embodiments for the magnetic deflection structure of FIGURE 8.

FIGURE 9 shows an axial sectional view of the output side of still another preferred embodiment of the instant invention.

FIGURE 10 is an end view of the preferred embodiment of FIGURE 9 looking in the direction of arrows 10-10'.

Making reference to FIGURE 1, there is shown therein a travelling-wave tube amplifier 1 whose presentation in FIGURE 1 is confined to the output end thereof for purposes of simplicity. The output end is shown in sectional fashion in the figure, and is comprised of a travelling-wave tube 2 and a periodic magnetic field device 3. The travelling-wave tube 2 is comprised of a vacuumized glass envelope 4 containing a helical slow-wave structure

5 and an output high-frequency coupler 8 comprised of a choke 7 and an antenna 6 secured to choke 7 adjacent an opening 7a provided therein.

A collector 10 positioned to the right of high-frequency coupler 8 is provided with a narrow cylindrical-shaped opening 9 projecting in the direction of the slow-wave structure. The extension 9 is hermetically sealed to vacuum envelope 4 at 9a. The radiator structure 11 embraces the outer surface of collector 10 for the purpose of carrying away heat generated by the collector.

10 The periodic magnetic field device 3 is disposed in a coaxial fashion about the travelling-wave tube 2, and is comprised of a plurality of axially magnetized hollow cylindrical permanent magnet members 12 and a plurality 15 of annular pole pieces 13 interspersed between the permanent magnet members. A waveguide 14 is inserted between the periodic magnetic field device 3 in the manner shown, and has a configuration which surrounds the antenna 6 of the output high-frequency coupler 8.

20 As can best be seen in FIGURE 2, the permanent magnet member 15 employed as the electron deflection magnetic structure, is positioned in close proximity to the collector end of the periodic magnetic field device 3. The permanent magnet 15 is a substantially cylindrical-shaped 25 permanent magnet member having a centrally located opening 15a. The permanent magnet member 15, however, is modified, prior to assembly into the structure, so as to produce an asymmetrical configuration by cutting off a side portion 16 thereof so as to yield a resultant structure capable of producing an axially asymmetric magnetic field relative to the longitudinal axis of the structure.

The structure, as shown in FIGURES 1 and 2, has been incorporated into a large-output travelling-wave tube, and it has been found to result in a significant reduction in the backward flow of secondary electrons emitted from the collector, as well as a significant reduction in irregular noise caused by the secondary electron emission.

Insofar as the specific planar configuration of the magnetic member 15 is concerned, it should be noted that member 15, which serves as the electron deflection magnetic structure, may be provided with other configurations which serve to produce an asymmetrical magnetic field relative to the longitudinal axis. For example, the magnet may be provided with a plurality of cut-away portions such 45 as the cut-away portions 16 and 16a, shown in FIGURE 2a. In addition thereto, more than one magnetic member having such a cut-away portion may be provided. For example, the magnetic member 12' may also be provided with a cut-away portion 16 in the same manner as the magnetic member 15, shown in FIGURE 2. Also, the plurality of magnetic members may be provided with additional cut-away portions, as shown in FIGURE 2a. Likewise, the shape and the dimensions of the cut-away portion, or portions, may assume a variety of configurations 55 so long as the desired axially asymmetric magnetic field is obtained. For example, the magnetic member 15 may be provided with one cut-away portion 16b, as shown in FIGURE 2b, or may be provided with a second cut-away portion 16b', as shown by the dotted lines of FIGURE 2b. As a further means of improving the effectiveness of the deflection structure, it is advantageous in some applications to remove the annular pole piece positioned closest to the collector with a view to further strengthening the axial asymmetry of the magnetic field.

60 For example, in the embodiment of FIGURE 1, it is possible to eliminate the annular pole piece 17 to enhance the asymmetrical magnetic field pattern.

To further emphasize the technical merits of the instant invention in conjunction with the preferred embodiment 70 of FIGURES 1 and 2, experimentation was conducted with a travelling-wave tube amplifier having a 6,000 megacycle operating frequency, a collector voltage of 2,000 volts, a slow-wave structure voltage of 3,400 volts, a collector current of 40 millamps, and a high-frequency output of 20 watts. In an embodiment having the above

operating characteristics and which did not incorporate the structure of the instant invention, the slow-wave structure current was found to be 0.28 millamps. By modifying the travelling-wave tube amplifier to incorporate a cut-away magnet 15 having an outer diameter of 34 millimeters, an inner diameter of 15 millimeters, a length of 9 millimeters, and a cut-away portion of segment shape in cross-section whose chord 16 was positioned distance $D=9$ millimeters from the central axis, the slow-wave structure current was found to be 0.15 millampere, resulting in almost a 50% reduction in current magnitude.

Referring to FIGURES 3 and 4, there is shown therein a second preferred embodiment of the travelling-wave tube amplifier wherein the electron deflecting magnetic structure, which is disposed at the collector end of the periodic magnetic field focussing device 3, is comprised of an axially magnetized permanent magnet member 19 having a centrally located opening 19a and a circular periphery forming a hollow cylindrical magnetic member. The magnetic by-pass 20 having an arcuate configuration, shown by the cross-sectional view of FIGURE 4, is disposed around a portion of the periphery portion of magnet 19. The arcuate magnetic by-pass 20 acts as a partial shunting device between the poles of the magnet 19 so as to yield a magnetic field having axial asymmetry along the axis of the apparatus. With the partial shunt aligned in the manner shown in FIGURES 3 and 4, it should be noted that the electron beam undergoes deflection which occurs in a direction perpendicular to the plane of the FIGURE 4 drawing.

Insofar as the embodiment of FIGURES 3 and 4 is concerned, the following comparative data was obtained:

A travelling-wave tube amplifier of the type set forth in conjunction with that used in determining the technical merits of the first preferred embodiment (of FIGURES 1 and 2) was employed and was found to yield a slow-wave structure current of 0.28 millampere when the operating values as set forth previously were applied to the assembly under test, and when no corrective measures were employed for the purpose of reducing slow-wave structure current.

Through modification of the travelling-wave tube amplifier so as to include a hollow cylindrical permanent magnet 19 having an outer diameter of 34 millimeters, an inner diameter of 15 millimeters, and a length of 9 millimeters; and a magnetic by-pass 20 formed of pure iron, having a wall thickness T of 0.8 millimeter, a width W of 9 millimeters and a length D_1 along the arc of 35 millimeters, was found to yield a slow-wave structure current of 0.13 millampere which is greater than a 50% reduction in current magnitude. It was further found that the travelling-wave tube amplifier would not oscillate even when the input or the output high-frequency circuits were short-circuited, and also that greatly improved impedance-matching characteristics were evident during operation of the device.

Whereas the by-pass device 20 may be formed as a separate element of the structure, it should be noted that an alternative and satisfactory approach is that of forming the magnetic by-pass 20 integrally with either one of or both of the annular pole pieces 13' and/or 17, as shown in FIGURE 3.

Referring now to FIGURES 5 and 6, there is shown therein a third embodiment of the instant invention which is substantially identical to that shown in FIGURES 3 and 4, except that the magnetic by-pass 20 positioned around the periphery of the permanent magnet member, is replaced by a magnetic by-pass member 21 which is disposed within the inner periphery of permanent magnet 19. The arcuate-shaped magnetic by-pass 21 is thus axially and asymmetrically arranged between the pole pieces 13' and 17 in surface contact with the side faces of magnet 19 so as to serve as a partial shunt between both poles of the magnet, and thereby yield a magnetic field along the axis having an axial asymmetrical pattern.

Experimentation with this embodiment was found to yield results substantially similar to those obtained through use of the embodiment of FIGURES 3 and 4 so as to thereby yield substantially similar technical merits thereto.

In much the same way as that described with respect to the embodiment of FIGURES 3 and 4, the magnetic by-pass member 21 may be integrally formed with one or both of the annular pole pieces 13' and 17.

As a further alternative, it should be noted that the magnetic by-pass member 20 of FIGURE 4 (or 21 of FIGURE 6) need not be a single member, but as a substitute, plural by-pass members may be employed and disposed about the permanent magnet 19, with the only requirement being that the axial asymmetrical magnetic field pattern be maintained.

The magnetic material employed in forming the by-pass member (20 or 21) may have any suitable magnetic characteristics. For example, the instant invention is useful even when a material exhibiting a negative temperature coefficient of magnetic permeability is employed with a view to producing temperature compensation of the axial magnetic field. More specifically stated, the magnetic flux produced by a permanent magnet generally decreases with an increase in temperature so that the axial magnetic field produced by the magnetic structure employed for electron deflection along the axis also decreases with this rise in temperature to cause a fluctuation in the effects of focusing of the electron beam and further of preventing backflow of secondary electrons. In order to compensate for such fluctuations in magnetic field strength, one effective measure which may be employed is set forth in detail in copending U.S. patent application Ser. No. 576,069, now abandoned, which describes in detail the use of tubular temperature compensation members formed of a magnetic material having a negative temperature coefficient of magnetic permeability. Such temperature compensation tubes are disposed between successive pairs of pole pieces 13 so as to shunt the respective permanent magnets. Thus, while temperature increases, decrease in the magnetic field strength of the permanent magnet members accompanying permeability changes occur in the temperature compensation tubes, causing the magnetic field branching through the tubes to be diverted toward the central axis of the amplifier tube apparatus, and hence to maintain a substantially constant magnetic field strength pattern. Use of a similar magnetic material for the by-pass members 20 (or 21) will yield a travelling-wave tube amplifier having stable focussing action for the electron beam as well as a deflection structure which prevents backflow of secondary electrons irrespective of temperature changes.

FIGURES 7 and 8 show a fourth embodiment of the travelling-wave tube amplifier structure employing an axially transversely magnetized hollow cylindrical permanent magnet member 22 for the electron deflection magnetic structure. The axially transversely magnetized hollow cylindrical permanent magnet 22 is secured to the right-hand face 23 of annular pole piece 17 which is disposed at the collector end of the periodic magnetic field focussing device 3. A non-magnetic annular-shaped support 24 maintains the magnet 22 a spaced distance from pole piece 17 so that this pole piece will not act as a shunting member for magnet 22. The magnetic poles for member 22 are indicated in FIGURE 7. The axially transverse magnetic field is generated in the region of the tubular-shaped extension 9 of collector 10, with the magnetic field lines being substantially perpendicular to the sheet of FIGURE 8.

The permanent magnet member 22 need not be a complete cylindrical member, and may be substituted by a horseshoe-shaped member 22', shown in FIGURE 8a, or a semicircular shaped member 22'', shown in FIGURE 8b, with the poles being arranged as shown in these figures.

FIGURES 9 and 10 show still another preferred embodiment of the instant invention wherein the travelling-wave tube amplifier structure 1 is provided with a pair of bar magnets 25 and 26 substituted for the axially transversely magnetized hollow cylindrical permanent magnet 22 described in the embodiment shown in FIGURES 7 through 8b. The bar magnets 25 and 26 are secured to the right-hand surface of annular-shaped pole piece 17 by means of non-magnetic supports 27 and 28 which maintain bar magnets a spaced distance from the surface 23 and hence from the pole piece 17 so as to cause the bar magnets to be substantially unaffected by pole piece 17. In addition thereto, the bar magnets 25 and 26 are so positioned as to concentrate the magnetic field pattern developed by the magnets in the immediate region of the extension 9 of collector 10. Considering FIGURE 10, it can be seen that the bar magnets are aligned along the diameter d of pole piece 17 such that poles of opposing polarity are arranged in face-to-face relation, producing a magnetic field perpendicular to the axis of the amplifier device. The magnetic field lines produced in the region of extension 9 are thereby parallel to the plane of FIGURE 9 so as to yield deflection characteristics which are substantially similar to those produced by the corresponding magnetic field of the embodiment of FIGURES 7 through 8b. As a further alternative, the pair of bar magnets, shown in FIGURES 9 and 10, may be replaced by a single bar magnet positioned either in the location of bar magnet 25 or bar magnet 26. In addition thereto, it should be noted that whether a single bar magnet is employed or whether a pair of bar magnets is employed, alignment may be affected along any diameter of the pole piece 17, the only requirement being that this diameter be aligned transverse (and preferably perpendicular) to the tube longitudinal axis.

All of the embodiments of FIGURES 1 through 10 described herein substantially operate in the following manner:

The electron beam 29 in any one of the embodiments moves from the left-hand end of the travelling-wave tube amplifier (not shown for purposes of simplicity) toward the right-hand or collector end thereof. The electron beam is substantially confined to the circular-shaped region between the helical-shaped slow-wave structure 5. The electron beam passes through the opening 7a and subsequently through the region of extension 9 provided on collector 10. In this region, the electrons are deflected away from and caused to deviate from the amplifier longitudinal axis under the action of the magnetic force provided by the deflection device of the instant invention which produces a magnetic field substantially perpendicularly aligned to the trajectory of the electrons, which field is an axially asymmetric magnetic field having a field component aligned orthogonal to the axis. Inasmuch as there is no focussing magnetic field within collector 10, the electron beam 29 diverges due to the space charge force and the electrons are thereby captured by collector 10 over a wide area of its interior surface 30. The travelling velocity of the electrons cause the electrons impinging upon the interior surface 30 to produce secondary electron emission. Although a portion of the secondary electrons produced by the electron beam impinging upon surface 30 with high velocity are again captured by the collector interior surface 30, the remaining electrons which are not so captured and which have velocity components directed toward slow-wave structure 5, are deflected perpendicularly to the axis when they approach the region of influence of the magnetic deflection structure such that the component of magnetic field produced by the electron deflection magnetic structure, which is orthogonal to the axis, causes the secondary electrons to be deflected and captured by the interior surface of extension 9 provided on collector 10. Thus, it can be seen that the magnetic deflection structure produces a very significant reduction in the amount

of secondary electrons flowing back toward the slow-wave structure 5 and the choke 7, further resulting in a significant reduction in the deterioration of various characteristics of the amplifier tube caused by the secondary electrons. Furthermore, the instant invention has the additional advantage of significantly reducing the harmful local heating of the collector, due to the fact that the electron beam 29 are captured by the collector over a wide area of interior surface 30 so as to greatly reduce the power consumption per unit surface area.

5
10
15

Whereas the magnetic field produced by the electron deflection magnetic structure of the embodiments of FIGURES 7-8 and 9-10 are described as having a magnetic field component which is orthogonal with the tube longitudinal axis, it should be further understood that this magnetic field component need not intersect the tube longitudinal axis at right angles, but may intersect at any other angle other than a right angle so long as the resulting magnetic field has a magnetic field component of a strength sufficient to deflect the electrons.

Although this invention has been described with respect to its preferred embodiments, it should be understood that many variations and modifications will now be obvious to those skilled in the art, and it is preferred, therefore, that the scope of the invention be limited not by the specific disclosure herein, but only by the appended claims.

The embodiments of the invention in which an exclusive privilege or property is claimed are defined as follows:

1. In a travelling-wave tube amplifier having a travelling-wave tube including a collector at one end thereof, and a periodic magnetic field device disposed coaxially about the travelling-wave tube, the improvement comprising an electron deflection magnetic structure positioned at the collector end of said periodic magnetic field device and adjacent the collector of said travelling-wave tube; said magnetic structure comprising a magnet for producing a magnetomotive force within said collector which force is asymmetric with respect to the axis of the magnetic field produced by said periodic magnetic field device, whereby the secondary electrons emitted from said collector are prevented from flowing back toward the slow-wave structure disposed on the side of the opening of said collector.
2. A travelling-wave tube amplifier set forth in claim 1 wherein said electron deflection magnetic structure is an axially magnetized hollow cylindrical permanent magnet formed into an axially asymmetric form by cutting away a side portion thereof.
3. A travelling-wave tube amplifier set forth in claim 1 wherein said electron deflection magnetic structure is an axially magnetized hollow cylindrical permanent magnet having a circumferentially partial magnetic by-pass member disposed along a portion of the periphery of said magnet.
4. A travelling-wave tube amplifier as set forth in claim 1 wherein said electron deflection magnetic structure is an axially magnetized hollow cylindrical permanent magnet having a circumferentially partial magnetic by-pass member disposed along a portion of the internal periphery of said magnet.
5. A travelling-wave tube amplifier as set forth in claim 1 wherein said electron deflection magnetic structure is a hollow cylindrical permanent magnet which is magnetized so as to produce a magnetic field component orthogonally intersecting the axis.
6. A travelling-wave tube amplifier as set forth in claim 1 wherein said electron deflection magnetic structure is a bar magnet producing a magnetic field component orthogonally intersecting the axis.
7. A travelling-wave tube amplifier as set forth in claim 3 wherein the magnetic by-pass is formed of a magnetic material having a predetermined negative temperature coefficient of magnetic permeability to com-

pensate for the reduction in magnetic strength of said permanent magnet with increasing temperature.

8. A travelling-wave tube amplifier as set forth in claim 4 wherein the magnetic by-pass is formed of a magnetic material having a predetermined negative temperature coefficient of magnetic permeability to compensate for the reduction in magnetic strength of said permanent magnet with increasing temperature.

9. A travelling-wave tube amplifier comprising: a travelling wave tube having a longitudinal axis and being comprised of

an elongated helical slow-wave structure surrounding said longitudinal axis;

a vacuumized envelope having a collector structure at one end thereof and containing said slow-wave structure.

an electron beam source for directing an electron beam along said longitudinal axis toward said collector;

an elongated periodic magnetic field focussing device disposed coaxially about said envelope between said electron source and said collector;

means for deflecting said electron beam positioned adjacent the end of said focussing device adjacent said collector;

said deflection means including a magnet for producing a magnetic field within said collector having a magnetic field component perpendicular to said longitudinal axis to prevent secondary electrons emitted from said collector from returning to said slow-wave structure.

10. The amplifier of claim 9 wherein said collector is a hollow tubular-shaped metallic member having an opening at a first end for receiving said electron beam and being sealed at its second end;

a first portion of said tubular collector adjacent said opening being narrower than the remaining tubular portion of said collector;

said envelope being joined to the exterior surface of said collector to effect said vacuumized condition.

11. The amplifier of claim 10 wherein said deflecting means is a substantially disc-shaped permanent magnetic

member having a centrally located aperture surrounding said collector first portion.

12. The amplifier of claim 11 wherein said permanent magnet member has a portion thereof removed substantially along a chord of said periphery; said chord intersection the periphery of said aperture at at least two points.

13. The amplifier of claim 11 wherein said permanent magnetic member has at least one pie-shaped segment removed from said disc.

14. The amplifier of claim 11 further comprising a thin walled, arcuate-shaped by-pass member sheathing a portion of the outer periphery of said disc-shaped member.

15. The amplifier of claim 11 further comprising a thin walled, arcuate-shaped by-pass member sheathing a portion of the inner periphery of said disc-shaped member.

16. The amplifier of claim 11 wherein said permanent magnet is magnetized in a direction transverse to said longitudinal axis to produce a magnetic field orthogonal to said axis.

17. The amplifier of claim 10 wherein said deflecting means is a substantially semicircular-shaped permanent magnet member magnetically polarized to produce a magnetic field orthogonal to said longitudinal axis.

18. The amplifier of claim 10 wherein said deflecting means is comprised of at least one permanently magnetized bar magnet having its poles aligned along an imaginary line orthogonal to said longitudinal axis.
